UNITED STATES PATENT OFFICE.

MYRON B. HAMMOND, OF BRIDGEPORT, CONNECTICUT, ASSIGNOR TO THE THOS. P. TAYLOR CO., A CORPORATION OF CONNECTICUT.

DESIGN FOR A GARTER.

47,999.

Specification for Design.

Patented Oct. 19, 1915.

Application filed July 31, 1915. Serial No. 43,005. Term of patent 7 years.

To all whom it may concern:

Be it known that I, MYRON B. HAMMOND, a citizen of the United States, residing at the city of Bridgeport, in the county of Fairfield and State of Connecticut, have invented a new, original, and ornamental Design for a Garter, of which the following is a specification, reference being had to the accompanying drawing, forming part thereof.

The figure is a front elevation of a garter showing my new design.

I claim:

The ornamental design for a garter, as shown.

MYRON B. HAMMOND.

Witnesses:

F. W. RUBBLE, Jr.,
M. T. LONGDEN.
